UNITED STATES PATENT OFFICE.

FREDERICK W. HOWELL, OF BUFFALO, NEW YORK, ASSIGNOR TO
MARGARET T. HOWELL, OF SAME PLACE.

FLOUR-PACKER.

SPECIFICATION forming part of Letters Patent No. 366,167, dated July 5, 1887.

Application filed February 9, 1886. Serial No. 191,348. (No model.)

To all whom it may concern:

Be it known that I, FREDERICK W. HOWELL, of the city of Buffalo, in the county of Erie and State of New York, have invented new and useful Improvements in Flour-Packers, of which the following is a specification.

This invention relates to an improvement in that class of flour-packers which are provided with a packing-tube containing a device whereby the flour is forced down into the barrel, sack, or other package, which is placed upon a receding platform whose downward movement is automatically arrested when the desired quantity of flour has been packed.

The object of this invention is to render the machine easily portable and more efficient and convenient in its operation, and to provide means for regulating the packing-pressure with great nicety.

My invention consists to that end of the improvements which will be hereinafter fully set forth, and pointed out in the claims.

In the accompanying drawings, consisting of three sheets, Figure 1 is a sectional elevation of my improved flour-packer. Fig. 2 is a fragmentary sectional elevation at right angles to Fig. 1, on an enlarged scale. Fig. 3 is a vertical sectional elevation of the movable bearing and shaft. Fig. 4 is a fragmentary vertical section of the upper portion of the packing-tube. Fig. 5 is a horizontal section in line $x-x$, Fig. 4. Fig. 6 is a vertical section through one of the supporting-posts and connecting parts. Fig. 7 is an elevation, on an enlarged scale, of one of the helical springs and connecting parts. Fig. 8 is a side elevation of one of the catches whereby the platform is held down when the packing-pressure is removed. Fig. 9 is a horizontal section in line $y-y$, Fig. 1, on an enlarged scale. Fig. 10 is a sectional elevation showing a modified construction of the packing-tube.

Like letters of reference refer to like parts in the several figures.

A represents the lower end or discharge-spout of the stationary flour-bin, and A' the receiving-hopper of the packer, connected by arms a with the upper ends of the posts of the packer. The upper end of the hopper A' fits against the lower end of the bin A, as shown in Fig. 1.

A² represents a movable band attached to the outer side of the hopper A' by clamps a' , so as to lap over the joint between the hopper A' and the bin A and prevent the escape of flour through said joint. Upon releasing the clamps a' the band A² is dropped down, thereby disconnecting the hopper from the bin and permitting the packer to be moved underneath another bin, to which it is connected by the band A², in the above-described manner. By this means one packer may be used to pack flour from several bins.

The hopper A' is provided with a valve or slide of any suitable or well-known construction for cutting off the supply of flour at desire.

a² represents the tubular throat of the hopper forming the upper stationary portion of the packing-tube, and B the lower portion of the packing-tube detachably secured to the throat a² by bolts b.

C represents a bevel gear-rim which surrounds the throat a² and turns upon supports c attached to the throat. These supports may be rollers or short bearing-pieces, or a ring which extends around the throat.

D represents a rotary tube which surrounds the stationary tube B, and which is detachably secured to a collar, d, which is attached to the under side of the gear-rim C. The tube D extends downwardly beyond the lower end of the packing-tube and is provided at its open lower end with a cross-piece, d', to which is secured a vertical shaft, d². The latter extends upwardly into the packing-tube B and carries packing-augers E E'. The upper end of the shaft d² is journaled in a cross-piece, d³, secured in the packing-tube. The lower cross-piece, d', may be constructed in the form of a packing-auger, if desired. By turning the gear-rim C the tube D and the shaft d² and augers E E' secured thereto are turned, so as to force the flour out of the packing-tube B into the barrel or other package. Upon disconnecting the packing-tube B from the throat a² and the tube D from the collar d the flour-forcing mechanism can be removed and replaced by a similar mechanism of smaller size, if desired.

In the construction represented in Fig. 10 the packing-tube B and the central shaft are

omitted and the packing-augers are directly attached to the rotating tube D. This construction is simpler than that shown in Fig. 1, and is especially adapted to pack barrels, as the latter are not liable to turn with the rotating tube.

f represents the horizontal driving-shaft, journaled in stationary bearings and provided at its outer end with a tight and loose pulley, 10 F F', and at its inner end with an internally-toothed gear-wheel, f'.

g represents the movable driving-shaft arranged near the inner end of the driving-shaft f and provided at its outer end with a pinion, 15 g', which engages with the gear-wheel f' and at its inner end with a bevel-gear, g'', which engages with the gear-rim C. The shaft g is journaled eccentrically in a bearing, g³, which is capable of turning in its seat in the frame 20 of the machine, so that by turning this bearing the shaft g is raised or lowered, thereby throwing the pinion g' out of or into gear with the wheel f'.

H H' represent the hollow vertical posts of 25 the main frame arranged on both sides of the packing-tube and connected at their upper ends to the arms a, which support the hopper A'.

I represents the receding platform, composed 30 of horizontal side pieces connected preferably at the rear of the machine by a cross-piece, I', and provided with upright tubular posts I², which guide the platform in its vertical movements upon vertical rods i i'. The latter are 35 secured with their lower ends to the base of the machine. The upper end of the rod i is secured to the post H by a bracket, i², and the upper end of the rod i' is secured to one of the arms a.

40 j represents spiral springs surrounding the posts H H' and resting with their lower ends upon collars j', which can be adjusted vertically on the posts for regulating the tension of the springs.

45 J represents cross-heads, which are secured with their inner ends to the tubular posts I² of the platform and which embrace with their outer ends the posts H H' and bear upon the upper ends of the springs j, so that the latter 50 are compressed as the platform is lowered.

k represents chains or ropes secured to the cross-heads J and running over pulleys k', which are attached to the posts H H'.

55 K represents weights secured to the end of the chains or ropes k in the hollow posts for the purpose of counterbalancing the weight of the truck and platform.

l represents rack-bars secured to the lower ends of the posts H H' and extending upwardly 60 on the inner sides of the posts.

L represents spring cases or drums turning upon arbors l' and provided at their peripheries with gear-rims which engage with the rack-bars l.

65 m represents a helical spring arranged in each of the drums L and secured with one end to the arbor l' and with the other to the drum,

so that the spring is wound up as the platform is lowered. The arbors l' are secured to sleeves M, which are attached to the tubular posts I² by set-screws m', so that the toothed drums can be disengaged from the rack-bars when not required for use by turning the sleeves M upon the posts l'.

N represents spring-cases provided with similar helical springs and turning upon arbors n, which are secured to brackets n'. The latter are attached to the arms a of the main frame. The spring-cases N are connected with the posts I² of the platform by straps n² in such manner that the springs are wound up as the platform is lowered.

O represents the vertical shifting-rod guided with its lower end in an opening in the base of the machine and connected at its upper end 85 to an arm, O', which slides upon the rod i above the tubular posts I². The arm O' is connected by a rod, O², with an arm, P, which is secured to the bearing g³ of the shaft g, so that by raising the shifting-rod O the arm P is 90 swung upwardly and the bearing g³ turned in such manner as to engage the pinion g' with the wheel f', while by lowering the rod O the bearing is turned in the opposite direction and the pinion g' is thrown out of gear with 95 the wheel f'.

p represents an arm, which is secured to the rod O below the platform in such manner that the latter comes in contact with the arm p and shifts the rod and throws the shaft g out of gear when the desired quantity of flour has been packed. As the platform approaches the upper limit of its movement the post I² strikes 100 against the arm O', lifts the latter, and throws the shaft g into gear when the platform reaches 105 its uppermost position, thus starting the packing mechanism automatically.

Q represents the truck, which is placed upon the platform I, and which supports the barrel, sack, or other package into which the flour is packed. The platform I is provided with rollers q, which facilitate running the truck upon and from the platform. The truck is provided with wheels q', so that it can be easily moved on the floor of the mill.

R represents catches pivoted to the base of the machine for securing the platform I in its lowest position. Each catch R is provided with an upper claw, r, and a lower claw, r'. The platform I is provided on its under side 120 with inwardly-projecting noses s, which engage with the catches R. The catches R on both sides of the machine are secured to the same rock-shaft r², and assume a backwardly-inclined position when the platform is elevated, as represented in Fig. 2. When the platform has nearly reached its lowest position, the noses s strike the lower claws, r', of the catches R, whereby the latter are turned forwardly so as to engage the upper claws, r, over 125 the noses s, as represented in Fig. 8, thereby locking the platform in position and permitting the truck Q with the package of flour to be removed from the platform.

r^3 is an arm pivoted to the base of the machine and connected with one of the hooks R by a rod, t, which is provided with a spring, t', whereby the rod is rendered extensible. 5 When the package filled with flour has been removed from the truck, the latter is moved back upon the platform. When the truck has nearly reached the proper position upon the platform, the rear edge of the truck strikes 10 the arm r^3 and swings the latter backwardly, thereby swinging the catches R backwardly and releasing their upper claws, r, from the noses s. The platform is now elevated by the reaction of the springs, and when it has nearly 15 reached its upper position the packing-augers are automatically set in motion, as above described. When the platform approaches its lowest position and the catches R are swung forwardly, the truck bears upon the arm r and 20 prevents the latter from moving with the catches R. The spring t' permits the arm r^3 to be held back by the truck, while the catches R move forwardly and interlock with the noses s. As soon as the truck is removed from the 25 platform the arm r^3 is drawn forward by the spring t'. The catches R are held in engagement with the noses s by the upward pressure which is exerted upon the platform by the compressed springs. When a shorter package 30 is to be packed, the noses s are removed and replaced by correspondingly longer noses, which depend further below the platform and engage with the catches R at the proper time.

In my improved packer the pressure of the 35 flour in the bin is exerted directly downward upon the flour in the barrel or other package, and assists materially in packing the flour.

Either of the spring devices which resist the downward movement of the platform may be 40 disconnected, or two or all of them may be used simultaneously, as the size of the package to be packed may require, thereby affording ready means for regulating the packing-pressure.

45 I claim as my invention—

1. In a flour-packer, the combination, with a receiving-hopper, of a packing-tube forming a straight downward continuation of said hopper, a packing-auger, and driving-gear surrounding the packing-tube, substantially as set forth.

50 2. In a flour-packer, the combination, with a packing-tube, of an annular driving-gear surrounding said tube, a packing-auger, and a rotating tube, whereby the auger is connected with the driving-gear, substantially as set forth.

55 3. The combination, with the stationary packing-tube B, of the surrounding rotating tube D, and a packing-auger arranged in the stationary tube and attached to the rotating tube, substantially as set forth.

4. The combination, with the stationary packing-tube B, of the surrounding rotating 65 tube D, provided at its lower end with a cross-piece, d', an upright shaft, d'', secured to said

cross-piece, and a packing-auger attached to said shaft, substantially as set forth.

5. The combination, with the throat a², of the gear-rim C, surrounding said throat, and 70 a rotating tube, D, removably attached to said rim and furnished with a packing-auger, substantially as set forth.

6. The combination, with the throat a², of the gear-rim C, surrounding said throat, a rotating 75 tube, D, removably attached to said rim, and a stationary tube, B, removably attached to the throat a², substantially as set forth.

7. The combination, with the throat a², provided with supports c, of the gear-rim C, turning 80 on said supports, and a tube, D, attached to said gear-rim and provided with a packing-auger, substantially as set forth.

8. In a flour-packer, the combination, with the auger mechanism, of the driving shaft f, 85 provided with a gear-wheel, f', and the shaft g, provided at its ends with gear-wheels g' and g'', and supported in a movable bearing, substantially as set forth.

9. In a flour-packer, the combination, with 90 the auger mechanism, of the driving shaft f, a shaft, g, provided at its ends with gear-wheels g' and g'', and a turning bearing, g³, in which the shaft g is eccentrically journaled, substantially as set forth.

95 10. The combination, with the auger mechanism, movable platform, and the movable driving-shaft, of mechanism, substantially as described, whereby the ascending platform throws the driving-shaft automatically into 100 gear with the auger mechanism, substantially as set forth.

11. The combination, with the auger mechanism and the movable platform, of the driving-shaft g, provided with gear-wheels g' g'', 105 a movable bearing, g³, in which the shaft g is journaled, an arm, O', and a rod, O'', whereby the ascending platform moves the bearing g³ and throws the driving shaft g into gear with the auger mechanism, substantially as set forth. 110

12. The combination, with the auger mechanism and the movable platform, of the driving-shaft g, provided with gear-wheels g' g'', a turning bearing, g³, in which the shaft g is journaled eccentrically, and which is provided 115 with an arm, P, a movable arm, O', and a rod, O'', connecting the arm O' with the arm P, substantially as set forth.

13. In a flour-packer, the combination, with the movable platform, of the hollow posts 120 H H', provided with pulleys k' and counter-balancing-weight K, arranged in said posts and connected with the platform by chains or ropes k running over the pulleys k', substantially as set forth.

125 14. In a flour-packer, the combination, with the movable platform, of the posts H H', the spiral springs j, surrounding said posts and resting upon collars j', attached to the posts, and cross-heads J, attached to the platform 130 and bearing upon the springs j, substantially as set forth.

15. In a flour-packer, the combination, with the movable platform, of a rack-bar, *l*, and a pressure-spring, *m*, provided with a gear-rim which engages with said rack-bar, and whereby the spring is wound up as the platform descends, substantially as set forth.

16. The combination, with the movable platform, of the toothed spring-case *L*, turning upon an arbor secured to the platform, a helical spring, *m*, connecting the case with the arbor, and a stationary rack-bar, *l*, with which the toothed spring-case engages, substantially as set forth.

17. The combination, with the main frame, of the vertical guide-rods *i i'*, secured thereto, and the movable platform provided with tubular posts *l*', which slide on the rods *i i'*, substantially as set forth.

18. In a flour-packer, the combination, with the movable platform, of a catch whereby the platform is locked in its lowest position, and

a wheeled truck adapted to release said catch upon being placed upon the platform, substantially as set forth.

19. In a flour-packer, the combination, with the movable platform, of the cases *N*, containing helical springs, and straps *n*', connecting said spring-cases with the movable platform, substantially as set forth.

20. The combination, with the movable platform provided with noses *s*, of pivoted catches *R* and a releasing-arm, *r*', connected with the catches *R* and projecting above the platform, whereby the platform is released upon placing the truck upon the same, substantially as set forth.

Witness my hand this 1st day of February, 1886.

FREDERICK W. HOWELL.
